(57) **CLAIM**

The ornamental design for a dispensing box holder, as
shown and described.

DESCRIPTION

FIG. 1 is a perspective view of a dispensing box holder
according to a first embodiment of the present invention;
FIG. 2 is a front elevation view of the dispensing box holder
embodiment of FIG. 1;

FIG. 3 is a back elevation view of the dispensing box holder
embodiment of FIG. 1;

FIG. 4 is a right side elevation view of the dispensing box
holder embodiment of FIG. 1;

FIG. 5 is a left side elevation view of the dispensing box
holder embodiment of FIG. 1;

FIG. 6 is a top plan view of the dispensing box holder
embodiment of FIG. 1;

FIG. 7 is a bottom plan view of the dispensing box holder
embodiment of FIG. 1;

FIG. 8 is a perspective view of a dispensing box holder
according to a second embodiment of the present invention;
FIG. 9 is a front elevation view of the dispensing box holder
embodiment of FIG. 8;

FIG. 10 is a back elevation view of the dispensing box
holder embodiment of FIG. 8;

FIG. 11 is a right side elevation view of the dispensing box
holder embodiment of FIG. 8;

FIG. 12 is a left side elevation view of the dispensing box
holder embodiment of FIG. 8;

FIG. 13 is a top plan view of the dispensing box holder
embodiment of FIG. 8; and,

FIG. 14 is a bottom plan view of the dispensing box holder
embodiment of FIG. 8.

In the drawings, the broken lines depict portions of the
dispensing box holder that form no part of the claimed
design.

1 Claim, 14 Drawing Sheets
